ELECTRICAL FIXTURE OR THE LIKE

George G. Ellner, Long Island, N.Y.

Application March 23, 1944, Serial No. 527,708

4 Claims. (Cl. 240—51.11)

1

This invention relates generally to electrical fixtures employing lamps or tubes for the emission of rays and has further reference to that class of electrical devices which generate the bactericidal band of the ultra-violet spectrum for killing bacteria, mold, etc., and for other germicidal or sterilizing purposes. It has more particular reference to fixtures for use with tubular gaseous lamps or mercury discharge devices designed for the emission of ultra-violet radiation for extermination of bacteria and for general sterilization.

In considering the production of efficient devices of the above nature, it is essential that provision be made for eliminating all hazards, for controlling and directing the ultra-violet radiation, and for increasing the ultra-violet intensity within the effective field of operation.

It is an object of the present invention to provide a complete unitary lamp and control assembly, wherein there is embodied in one complete assembly transformer, sockets, reflector, wiring for the primary and secondary of the transformer and other auxiliary control devices required for operation and control of the lamp.

It is a further object of the present invention to provide in a self-contained unit, an electric lamp of the fluorescent tube type, an ultra-violet ray lamp for producing sterilizing germicidal and like radiations, sockets, wiring, transformer or transformers, and other auxiliary controls.

It is a further object of the present invention to provide means housing, controlling and directing the radiation of electrically operated lamps and more specifically bactericidal or sterilizing ultra-violet ray emitting lamps or the combination of such lamps with lamps of the fluorescent tube type.

A still further object of the present invention is to provide self-contained units of the above types which may be employed in ceiling fixtures, wall fixtures, or floor or table fixtures.

Another object of the present invention is to incorporate in the above-mentioned assemblies or units, means for producing air currents through the fixtures embodying the same so that a circulatory sterilized environment may be established in the medium in which the lamp is placed.

This invention accordingly consists in the features of construction, combination of parts and in the unique relations of the members and in the relative proportioning and disposition thereof, all as more completely outlined herein.

To enable others skilled in the art so fully to

comprehend the underlying features thereof that they may embody the same by the modifications in structure and relation contemplated by this invention, a drawing depicting certain forms of the invention has been annexed as a part of this disclosure, and in such drawing, like characters of reference denote corresponding parts throughout all the views, of which:

Fig. 1 is a sectional view of a lamp fixture made in accordance with the invention;

Fig. 2 is a front elevational view of a lamp fixture made in accordance with the invention in a modified form;

Fig. 3 is a sectional view taken along line 3—3 of Fig. 2;

Fig. 4 is a diagrammatic front elevational view in section showing means for producing an air flow through the fixture and over the lamps;

Fig. 5 is an end view of Fig. 4;

Fig. 6 is a partial front elevation, partly broken away, disclosing the invention in a still further modified form;

Fig. 7 is a sectional view taken along line 7—7 of Fig. 6; and

Fig. 8 is a front elevational view in section, taken on the line 8—8 of Fig. 1.

Referring now more particularly to the drawing:

In Fig. 1 the lamp fixture generally indicated by the numeral 10, may comprise a curved shell 11 closed by end walls 15 and being flared outward as at 12 and having a top opening, and a bottom opening 13 formed by bending back the portions 14 of the bottom. In substantially the center of the fixture is disposed an assembly including a channelled or substantially tubular member 16 on which is mounted a transformer 17. Hollow member 16 has a partition 18 dividing the same into two compartments 18a and 18b, for containing conductors 20 and 21, respectively.

Also secured to member 16, are the brackets and sockets 21, 22 in which may be mounted in conventional manner two electric lamps or tubes 23, 24 adapted to emit radiant energy, such as, ultra-violet or infra-red rays and luminous rays. Both lamps may be of the type adapted to radiate germicidal or sterilizing rays or one may be of this type and the other an electric lamp of the fluorescent type. In the event that the lamps are of the low voltage operating type then a reactor would be used instead of the transformer, and in the event a lamp of each type is employed, then each would have its respective auxiliary equipment mounted on member 16.

Suitable reflecting means 25 may be mounted on the channel 16 or on the brackets 21, 22.

Each reflector 25 preferably comprises two parallel members 25a, 25b concave in cross-section and joined together. These reflectors are mounted in such a manner as to increase the efficiency of the radiation by reflecting the rays, which would otherwise be lost, outwardly from shell 11. Furthermore, reflectors 25 act as shields against ultra-violet or other rays passing through opening 13.

Referring to Figs. 2 and 3, the fixture shown differs somewhat from that seen in Fig. 1, in that the assembly includes a central vertical partition 30 extending from ends 31 and having mounted thereon on both sides hollow supports or channels 32, 33 forming with partition or wall 30, housings. Each channel or hollow 32, 33, is divided into three compartments 34, 35, 36.

Compartments 34 and 35 contain the high and low voltage wires 37, 38, respectively, for the ultra-violet ray emitting lamps 42 mounted in sockets on brackets 41, while the compartment 36 contains the two wires 39 for the fluorescent lamps 44 mounted in sockets on brackets 43. In this instance two transformers 40, 40a are respectively mounted on channels 32, 33. However, in the event, that the lamps 42 are of the low voltage type, then reactors would be substituted for the transformers 40, 40a.

As particularly seen in Figs. 2 and 3, there has been provided herein an electrical fixture in which the shell 11 has symmetrical parts with respect to a central vertical axis; the substantially vertical wall 30 is located at said axis and the supports 32, 33, upon which the operating auxiliaries 40, 40a are mounted and in the hollows of which are received the wires, are respectively and symmetrically attached to opposite sides of this wall, with the hollow portions of the supports located at their respective rears; the supports and the said wall forming housings for the wires, the sockets for the ray-emission lamps being mounted on the supports. The fixture seen in Fig. 1 has the substantially tubular or hollow member 16 located at the central vertical axis thereof.

The lamp fixtures illustrated, may be either of the suspended type, in which case chains 50 (Fig. 1) may be utilized engaging in holes 51 in the end walls 15 or 31 of Fig. 1 or 3, respectively; or they may be of the floor stand type in which case conventional floor stand means may be provided, as indicated at 52 (Fig. 2).

It is desirable that the medium or environment in which the fixture is placed, be sterilized, for which purpose means are provided to produce air currents through the length of the fixture, which currents will pass through openings in the ends of the fixture.

As shown in Figs. 4 and 5, the fixtures may be provided with double end walls 60-61 and 62-63, respectively. Between each double wall 60-61 and 62-63, respectively, are located propellers 64, 65, mounted on driven shaft 66. Shaft 66 is located such as not to interfere with the location of the assembly of all of the operating parts. Shaft 66 is mounted on bearings 67, 68 which are part of the inner walls 60 and 62, respectively, and extends the entire length of the lamp. Propellers 64 and 65 will draw air through perforations 70, 71, in end walls 61, 62, respectively, and will drive the air out through perforations 69, 72 in end walls 60, 63, respectively. The perforations 69 located in end wall 60 are staggered in relation to perforations 70 in end 75

wall 61, while the perforations 71 in end wall 62 are staggered in relation to the perforations 72 in end wall 63. Thus, no openings in the end walls will be visible from outside the fixture through which ultra-violet or other eye-detrimental rays may be radiated from the lamps within the fixture.

Shaft 66 may be driven by means of a motor 13. Motor 13 is connected to shaft 66 by pulleys 14, 15, and belt 16.

Motor 13, shaft 66, pulleys 14, 15, belt 16, inner end walls 60, 62 and propellers 64, 65 are preferably all mounted on the operating assembly forming integral parts of a complete unit.

As shown in Figs. 6 and 7, the device may be adapted as a wall fixture, in which case the shell 80 is secured to a wall plate 81, having perforations 82 for suspension purposes.

Secured to plate 81 is a channel member 83 divided into compartments 84, 87, containing the high and low voltage wires 86, 85, respectively. A transformer 88 is mounted on channel 83, which channel also supports the lamp brackets and sockets 89 for lamp or tube 90. Located within housing 80 is a reflecting means 91, preferably comprised of two parallelly disposed joined members 92, 93, each member being concave in cross-section.

It is understood that the reflector means 25 of Fig. 1 may be applied to the fixtures shown in Figs. 3 and 7, in lieu of reflectors 92, 93.

The combination of the air circulating system of Fig. 4 with the lamp shown in Fig. 1 is illustrated in Fig. 8 in which reference numerals 60 through 76 have the same significance as numerals 60 through 76, respectively, in Fig. 4. The motor 13', the pulley 15', the belt 16' and the shaft 66' are also shown in Fig. 1. From Fig. 8 it will be seen that the shaft 66', being lodged in bearings 97, 98, is connected with the propellers 64', 65' by way of respective pairs of pulleys 94, 95 and respective belts 96, the pulleys 94 being mounted on two stud shafts 99, 100 carrying the propellers 65' and 64', respectively. The operation of the system shown in Fig. 8 is identical with that shown in Fig. 4.

This application is a continuation in part of my copending application, Serial Number 465,232, which eventuated into Patent Number 2,375,354 on May 8, 1945.

From the foregoing description taken in connection with the accompanying drawing, it is apparent that improved simple, practical and inexpensive devices for the purpose intended are provided. It is apparent, however, that changes and modifications may be made by skilled persons without departing from the true spirit and scope of the invention as outlined in the appended claims.

Having thus described my invention, what I claim as new and desire to secure by Letters Patent, is:

1. An electrical fixture comprising a shell, a support in said shell, said support being hollow, a partition in said support dividing same into sections, a transformer mounted on said support, electrical wiring connected to the primary of said transformer and disposed within one of said sections, other electrical wiring connected to the secondary of said transformer and disposed within another of said sections, sockets mounted on said support, an ultra-violet radiating lamp connected to said sockets, said shell having spaced perforated end walls, a propeller adjacent each of

said end walls, a shaft connecting said propellers, and means for driving said shaft.

2. An electrical fixture comprising a shell, a support in said shell, said support having a channel, an operating auxiliary mounted on said support, electrical wires connected to said auxiliary and disposed in said channel, sockets mounted on said support, an ultra-violet radiating lamp connected to said sockets, said shell having perforated end walls, a propeller adjacent each of said end walls, a shaft connecting said propellers, and means mounted on said support for driving said shaft.

3. An electrical fixture comprising a shell, a support in said shell, said support having a channel, an operating auxiliary mounted on said support, electrical wiring connected to said auxiliary and disposed in said channel, sockets mounted on said support, an ultra-violet radiating lamp connected to said sockets, said shell having two pairs of perforated end walls, the perforations in one of the walls of each pair being staggered with respect to the perforations in the other wall, a propeller disposed between the end walls of each pair, respectively, a shaft connecting said propellers and extending longitudinally of said support, and means mounted on said support for driving said shaft.

4. An electrical fixture comprising a shell, a hollow support in said shell, a partition in said support dividing same into sections, a transformer mounted on said support, electrical wiring connected to the primary of said transformer and disposed within one of said sections, other electrical wiring connected to the secondary of said transformer and disposed within another of said

sections, sockets mounted on said support, an ultra-violet lamp connected to said sockets, said shell having two pairs of perforated end walls, the perforations in one of the walls of each pair being staggered with respect to the perforations in the other wall, a propeller disposed between the end walls of each pair, respectively, a motor mounted on said support, a shaft connecting said propellers and extending longitudinally of said support, and means operatively connecting said motor with said shaft.

GEORGE G. ELLNER.
